US00D912685S

(12) **United States Design Patent** (10) **Patent No.:** **US D912,685 S**
(45) **Date of Patent:** **** Mar. 9, 2021**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Cedric Kiefer**, Berlin (DE); **Henryk Wollik**, Berlin (DE); **Jae Julien**, Seoul (KR); **Yoojin Choi**, Seoul (KR); **Heejin Ko**, Seoul (KR); **Ji Hyae Kim**, Seoul (KR); **Hyeryung Kim**, Seoul (KR); **Jihyun Lee**, Seoul (KR); **Kitae Kim**, Seoul (KR)

(73) Assignee: **SAMSUNG ELECTRONICS CO., LTD.**, Gyeonggi-Do (KR)

(**) Term: **15 Years**

(21) Appl. No.: **29/687,229**

(22) Filed: **Apr. 11, 2019**

(30) **Foreign Application Priority Data**

Oct. 12, 2018 (KR) 30-2018-0047018

(57)

CLAIM

The ornamental design for a display screen or portion thereof with graphical user interface, as shown and described.

DESCRIPTION

The FIGURE is a front view of a display screen or portion thereof with graphical user interface, showing our new design.

The broken line showing of the display screen or portion thereof forms no part of the claimed design.
